Attorney, Agent, or Firm — Watts Law LLC; John A. Yirga, Esq.

(57) CLAIM

The ornamental design for a swim vest, as shown and described.

DESCRIPTION

FIG. 1 is a front perspective view of the swim vest, showing our new design;

FIG. 2 is a front elevation view thereof;

FIG. 3 is a rear elevation view thereof;

FIG. 4 is a right-side view thereof;

FIG. 5 is a left-side view thereof;

FIG. 6 is a top plan view thereof; and,

FIG. 7 is a bottom plan view thereof.

The dash-dash broken lines shown along the perimeter of the swim vest in FIGS. 1, 2, 3, 6, and 7 illustrates seaming in the fabric.

1 Claim, 7 Drawing Sheets
